UNITED STATES PATENT OFFICE.

STEPHEN C. RADFORD, OF OSHKOSH, WISCONSIN.

COMBINED WATER AND CHEMICAL SPRINKLING SYSTEM.

No. 845,892.

Specification of Letters Patent.

Patented March 5, 1907.

Application filed July 23, 1906. Serial No. 327,303.

To all whom it may concern:

Be it known that I, STEPHEN C. RADFORD, residing in Oshkosh, in the county of Winnebago and State of Wisconsin, have invented 5 new and useful Improvements in a Combined Water and Chemical Sprinkling System, of which the following is a description, reference being had to the accompanying drawings, which are a part of this specification.

10 My invention has relation to a combined water and chemical sprinkling system.

In the ordinary form of sprinkler system water alone is used as the sprinkling medium, and in some forms of these systems the piping running through a building is provided 15 with a series of small discharge openings or apertures which are normally closed by fusible plugs, and the pipes are filled with air which acts to hold back the water, and hence prevent freezing in cold weather. 20 These fusible plugs when a fire occurs in a building will melt by reason of the heat generated by the fire, and hence the discharge-apertures are opened and numerous 25 vents thereby provided for the escape of the air, the water being then free to flow into the system of piping and to escape through the small openings or apertures thereof by reason of the air-pressure being thus relieved.

30 In other forms of water-sprinkling systems the openings or apertures in the pipes are not closed by fusible plugs, and the water is held back by a thermostatically-operated valve, which will open under the influence of 35 heat generated by a fire, and thus permit the water to flow into the system of pipes and discharge through the small discharge openings or apertures thereof.

It is the primary object of my invention 40 to provide a sprinkler system operating along either of the above-indicated lines, but which at the same time is of such construction as to combine with the water-sprinkling feature of the old systems a chemical 45 sprinkling, and also so constructed that the water and chemicals may be sprinkled simultaneously or independently of each other.

With the above primary object and other 50 incidental objects in view the invention consists of the devices and parts or the equivalents thereof, as hereinafter more fully set forth.

In the accompanying drawings, Figure 1 55 is an elevation of the complete system, parts in section and parts broken away. Fig. 2

is a view at right angles to Fig. 1 of the chemical-tank, the said tank being in section; and Fig. 3 is a plan view of the tilting mechanism.

60 Referring to the drawings, the numeral 4 indicates a main water-pipe leading from any suitable source of water-supply and extended upwardly and having connected to its upper end by means of a coupling 5 a pipe 6, from which the water is sprinkled or discharged, the said pipe being provided with a series of discharge openings or apertures, which may or may not be normally closed by fusible plugs, depending upon the particular system employed, as hereinbefore referred to. Pipe 4 is provided with a hand-operated valve 7, whereby the supply of water from the main supply into said pipe 4 may be cut off at any time.

75 The numeral 8 indicates a chemical-tank which has leading from its bottom a suitable valve-controlled drain-pipe 9, and the top of this tank is provided with a covered man-hole 10, whereby admission to the tank for 80 the purpose of cleaning may be readily gained at any time. Pipe 4 has extending therefrom a branch pipe 11, which leads into the lower portion of tank 8. This pipe 11 is provided with a hand-operated valve 85 12 and with a check-valve 13.

75 Secured to the under side of the top of the tank 8 is a bracket 14. This bracket is advantageously made of upper and lower sections with the arms of the upper section 90 provided with a series of apertures 15 to receive bolts 16, passed through the arms of the lower section to permit the bracket to be originally set so as to extend downwardly into the tank the proper distance. The 95 arms of the bracket are provided with inward bends 17 17 and are continued downwardly from these inward bends to form extensions 18 18, which extensions are provided with diagonally-extending terminals, 100 which terminals are formed with a horizontal cup-shaped support 19 for holding a fragile receptacle 20, said receptacle containing a suitable liquid chemical, such as sulfuric acid, or any other desirable liquid chemical. Between the arms of the bracket and just above the inward bends 17 is a receptacle 21, adapted to contain a solid chemical, such as sodium carbonate in a powdered form, or any other desirable solid chemical. The under side of 105 the receptacle 21, near one end, is provided with a lug 22, which lies between two lugs

23 23, extending upwardly from the inward bends 17, a pivot-pin 24 passing through the several lugs and adapting the receptacle to turn thereon. Depending from the under 5 side of the receptacle, at the front and rear ends thereof, are legs or standards 25 25, which at their lower ends are secured to a longitudinal rail 26. This rail 26 has depending therefrom connecting-rods 27 27, the lower ends of said rods being bifurcated and the furcate parts provided with eyes which support therein the ends of lower rails 28 28. The rails 26 and 28 28 form a runway for a weighted ball 29, and this runway is 10 tiltable with the receptacle 21 on the pivot-pin 24. Extending from one end of the runway is an arm 30, which at its outer end carries an adjustable contact 31, preferably in the form of a screw passing through a 15 threaded opening in the end of arm 30. Projecting from the opposite end of the runway is another arm 32, which carries an adjustable contact 33, also preferably in the form of a screw passing through a threaded opening in said arm 32.

Pivoted on a stud 34, projecting laterally from one of the depending extensions 18 of the bracket, is a float-ball arm 35, said arm carrying at its outer end a float-ball 36.

30 Leading from the lower portion of the chemical-tank and extending upwardly is a pipe 37, which at its upper end is coupled to a short branch pipe 38, which latter extends and is coupled to the coupling 5. In this 35 short branch pipe is a check-valve 39. Pipe 37 has also extending therefrom and through the side of the chemical-tank and into said tank for a slight distance a short pipe 40, the inner end thereof being beveled to form 40 a valve-seat. Pivoted to the upper edge of the inner end of this short pipe is a flap-valve 41, having an extension or wing 42 secured thereto and extending inwardly therefrom. This wing is in position to be contacted with by the adjustable contact 33, which contact when the runway is in its normal horizontal position, as shown in Fig. 1, 45 is in engagement with the wing of the flap-valve and holds said valve in an open position.

50 The numeral 43 indicates an auxiliary tank having a valve-controlled water-inlet pipe 44 extending from a suitable source of supply leading through the side thereof. From the 55 bottom of this tank extends a valve-controlled drain-tube 45, and the top of the tank is provided with a covered manhole 46, whereby convenient access to the interior of the tank can be obtained for cleaning purposes. Connecting with the top of this auxiliary tank is a valve-controlled pipe 47 for conducting air or gas into the upper portion of the tank and filling the space above the surface of the water in the tank.

60 The bottom of the tank is provided with

an opening in which is fitted a tube 48, having its upper end in the form of a valve-seat 49 and having connected to its outer lower end a pipe 50, which leads to and connects with an opening in one side of the chemical- 70 tank 8. Pipe 50 is provided with a hand-operated valve 51 and with a check-valve 52. The discharge-opening in the bottom of the auxiliary tank is controlled by means of a valve 53, carried at the lower portion of a 75 float-ball 54 and adapted to seat itself on the valve-seat 49 when the float-ball is not held up by the buoyancy of the liquid contents of the tank. Valve 53 is provided with a depending guide-stem 55, which passes through 80 and is guided in an opening in a guide 56.

It will be understood that water in the chemical-tank is prevented from rising in the tank, and therefore maintains a certain level in the tank by reason of the resistance 85 offered by the column of air or other gas above the surface of the water and in the system of piping 6. In the case of the auxiliary tank 43 the water is prevented from rising in this tank and is consequently 90 maintained at a certain level by reason of the pressure of the air or gas above the column of water, said air or gas being admitted through the pipe 47.

If my invention is used in connection with 95 a system wherein fusible plugs are employed in the piping 6, the air or gas is of course free to enter the said piping, and this air acts to hold back or prevent the sprinkling agent from entering the said piping and 100 to be thereby subject to freezing in cold weather. Instead of having the piping 6 filled with air for the purpose of holding back the water and preventing freezing under the conditions stated I may employ a valve-controlled pipe 57, which extends from any suitable 105 source of gas-supply and conducts said gas into the piping 6. The gas so admitted to the piping 6 acts normally to hold back the water, but when a fire occurs will 110 escape through the discharge-openings of the piping 6 and act as a medium for assisting in extinguishing the fire.

In cases where my invention is employed in connection with a thermostatically-operated valve in the piping 6 this valve will of course prevent the water from entering said piping under normal conditions, and thereby prevent freezing without the necessity of the piping 6 being filled with air, as in the other 115 case.

When a fire occurs and in case the fusible plugs are used as fillers for the discharge-openings, these plugs when a certain degree of heat is generated from a fire will melt, and the slight quantity of air in the piping 6 will first escape, and with the escape of this air the water in the pipe 37 will rise in said pipe, raising check-valve 39 and passing into piping 6 and out of the discharge-openings of 120 125 130

CRAFTSMAN

said piping, or in case the piping 6 is provided with the thermostatically-operated valve the heat from the fire will open this valve and allow the water to take the same course. The 5 moment the fusible plugs are melted or the thermostatically-operated valve opened air-pressure is relieved in the tank 8, and hence water from the main under pressure will pass through pipe 11 and enter said tank 8, and as 10 this water rises it will lift the float-ball 36, and when said ball is elevated a certain distance it strikes the contact 31, and thereby tilts the runway sufficiently to cause the ball 29 to roll down said runway, and there- 15 by complete the tilting of the runway, together with the receptacle 21, and permitting the discharge of the solid chemicals from the receptacle. The tilting of the runway will also have the effect of removing contact 33 20 from the wing 42 of valve 41, and hence said valve will close and prevent further escape of air. The tilting of the runway further has the effect of bringing the ball 29 into forcible engagement with and the consequent break- 25 ing of the fragile receptacle 20, allowing the liquid chemicals contained in said receptacle to escape. The chemicals escaping from the receptacles 20 and 21 causes the formation of a gas, which fills the space above the water 30 and produces a pressure greater than the pressure exerted by the head of water from the main. This pressure causes the water in the tank which is impregnated with the chemicals to flow upwardly through the pipe 37, lifting valve 39 and passing into piping 6 and escaping through the discharge-openings of said piping. It is obvious that the pressure above the surface of the liquid cannot cause the said liquid to escape through 35 pipe 11, as the check-valve 13 prevents this, and consequently the only escape for the liquid is through the pipe 37, as just explained. When the level of the liquid in the tank 8 is lowered to such an extent as to remove the 40 float-ball 36 from the contact 31, the runway and the receptacle 21, secured thereto, are tilted back by hand to normal horizontal position, the ball 29 then traveling back to its initial position. I provide a stop 58, 45 against which the lower rail 28 strike, so as to stop the movement of the runway when it reaches the horizontal position. Of course after a fire and before the device can again be used it is necessary to recharge the receptacle 21 and to place a newly-filled fragile receptacle 20 in the cup 19. On this return movement of the runway the contact 33 is brought into engagement with the wing 42 and the flap-valve 41 again opened. The 50 forcing of the chemically-impregnated water up the pipe 37 and out through the discharge-openings of the piping 6 necessarily causes a discharge of the chemical liquid in addition to the discharge of water into the burning 55 building, and thus very materially assisting

in the extinguishment of the fire. After the tank 8 has completed its work in discharging the chemically-impregnated liquid and the receptacles 20 and 21 are being recharged the chemical-tank can be cut out of the system 70 by closing the hand-operated valve 12, and the water-sprinkling system through the pipe 4 alone utilized. It is also very evident that whenever desired the water-sprinkling system can be cut out by closing the hand-operated valve 7 and only the chemical-sprinkling system employed. 75

Insurance companies require in order to make a standard sprinkling system at least two sources of water-supply—viz., a main supply and an auxiliary supply—so that if for any reason the supply from the main fails to operate the auxiliary supply can then be depended upon. In my invention one auxiliary supply is obtained through the 80 auxiliary tank 43, and the water in this tank when the piping 6 by reason of the heat is free to permit of discharge through the discharge openings or apertures of said piping, and the air-pressure in the piping thus relieved is forced by the pressure of air there- 85 above down pipe 50, raising check-valve 52 and entering tank 8 and acting in exactly the same manner as the water which enters said tank through the pipe 11. In fact, if de- 90 sired, water may enter tank 8 simultaneously through pipes 11 and 50. When the level of the water in tank 43 falls to a certain extent, the float-ball 54 lowers and causes valve 53 to close the discharge-opening in 95 said tank, and thus prevent the escape of the column of air above the water through the pipe 50 and into the system and which escape, it is obvious, during a conflagration would have a tendency to increase combus- 100 tion. However, if it is contemplated that gas be discharged into the upper portion of tank 43 through the pipe 47 instead of air, in this case the float-ball 54 and valve 53 would not be necessary, inasmuch as the escape of 105 gas through the pipe 50 and into the system during a conflagration would not be at all undesirable; but, in fact, the gas would be of such nature as to assist in putting out the fire, the gas being of such nature that it will 110 not burn or support combustion—such, for instance, as carbon dioxid. 115

While I have described certain details of construction, yet I do not wish to be understood as limiting myself specifically thereto, 120 as variations and modifications may be resorted to for accomplishing the functions of my invention without departing from the spirit and scope of the invention. For instance, the particular form of tilting mechanism for discharging the solid chemicals and the liquid chemicals is not absolutely necessary, as any desired form of mechanism which will discharge said chemicals on the 125 rising of the water in the tank 8 or when the 130

- SEARCHED

FILED
1. sprinkler-heads are open are within the spirit and scope of my invention. In fact, in some instances the sodium carbonate or some equivalent solid chemical may be placed 5 in solution in the water in the chemical-tank, and in such case the tilting of a receptacle containing such solid chemicals would not be necessary and only the discharging of the liquid chemical provided for, or, again, the arrangement might be such that only a dumping of the receptacle 21 containing the solid chemical is provided for, the only essential feature being that there should be means provided for preventing the escape of 10 the gas from the tank 8 when the chemical-sprinkling liquid is formed in order to provide the pressure necessary to force said chemical liquid out of the tank 8 and up the pipe 37.
- 20 When desired, the valve 41 may be dispensed with, and the gas generated by the discharge of the chemicals will then pass through pipe 40 into the system and be discharged instead of the water.
- 25 For safety in operation it is preferred to provide the tank 8 with a water-gage 59, showing the level of water therein, a pressure-gage 60, and a safety-valve 61, by means of which the tank may be vented in 30 event of the discharge of chemicals into the water at a time when the sprinkler-heads are closed. For convenience the auxiliary tank also is provided with a pressure-gage 62 and a water-gage 63.
- 35 Wherever the term "air" is employed herein referring to the medium normally contained in the system, it is to be understood that a liquid or gas which will not support combustion may be substituted.
- 40 What I claim as my invention is—
1. In a sprinkler system, the combination of a chemical-tank having a column of water therein and an air-filled space above the column of water, an inlet-pipe leading into the tank for conducting the water into said tank, which water is normally maintained at a certain level by the excess pressure above the column of water, an outlet-pipe leading from said tank, a system of piping with which the outlet-pipe connects, heat-operated means for causing the piping to open up and thereby permit the extinguishing agent to sprinkle and discharge from said piping, when a fire occurs, a branch pipe leading from the outlet-pipe and through the side of the tank, a pivoted valve at the inner open end of the branch pipe, a tiltably-carried and adjustable contact normally engaging the valve in a manner to hold said valve open, means, when a fire occurs, for chemically charging the water in the tank, and a float-ball adapted, when the system of piping is opened up by the heat generated from a fire and the air-pressure on the water is thereby relieved, to be raised by the then inflowing water, and when so raised to operate upon the contact and thereby remove said contact from engagement with the valve and permit a closing of said valve.
  2. In a sprinkler system, the combination of a chemical-tank having a column of water therein and an air-filled space above the column of water, an inlet-pipe leading into the tank for conducting water into said tank, which water is normally maintained at a certain level by the excess pressure above the column of water, an outlet-pipe leading from the tank, a system of piping with which the outlet-pipe connects, heat-operated means for causing the piping to open up and thereby permit the extinguishing agent to sprinkle and discharge from the piping, when a fire occurs, a branch pipe leading from the outlet-pipe and through the side of the tank, a pivoted valve at the inner open end of the branch pipe, a tiltably-carried contact normally engaging the valve in a manner to hold said valve open, means, when a fire occurs, for chemically charging the water in the tank, and a float-ball adapted, when the system of piping is opened up by the heat generated from a fire and the air-pressure on the water is thereby relieved, to be raised by the then inflowing water, and when so raised to operate upon the contact and thereby remove said contact from engagement with the valve and permit a closing of said valve.
  3. In a sprinkler system, the combination of a chemical-tank having a column of water therein and an air-filled space above the column of water, an inlet-pipe leading into the tank for conducting the water into said tank, which water is normally maintained at a certain level by the excess pressure above the column of water, an outlet-pipe leading from the tank, a system of piping with which the outlet-pipe connects, heat-operated means for causing the piping to open up and thereby permit the extinguishing agent to sprinkle and discharge from the piping, when a fire occurs, a branch pipe leading from the outlet-pipe and through the side of the tank, a pivoted valve at the inner open end of the branch pipe, a tiltably-carried and adjustable contact normally engaging the valve in a manner to hold said valve open, means, when a fire occurs, for chemically charging the water in the tank, and a float-ball adapted, when the system of piping is opened up by the heat generated from a fire and the air-pressure on the water is thereby relieved, to be raised by the then inflowing water, and when so raised to operate upon the contact and thereby remove said contact from engagement with the valve and permit a closing of said valve.
  4. In a sprinkler system, the combination of a chemical-tank, having a column of water therein and an air-filled space above the water, an inlet-pipe leading into the tank for conducting the water into said tank, which water is normally maintained at a certain level by the excessive pressure above the col-

DRAFTSMAN

umn of water, an outlet-pipe leading from the tank, a system of piping with which the outlet-pipe connects, heat-operated means for causing the piping to open up and thereby 5 permit the extinguishing agent to sprinkle and discharge from the piping, a branch pipe leading from the outlet-pipe and extending through the side of the tank, a valve at the inner open end of the branch pipe, means for 10 normally holding this valve at an open position, a tilttable runway in the tank having a weighted ball therein adapted to roll from one end of the runway to the opposite end thereof, when said runway is tilted, a float- 15 ball adapted, when the system of piping is opened up by the heat generated from a fire and air-pressure on the water is thereby relieved, to be raised by the then inflowing water, and when so raised to act upon and 20 tilt one end of the runway so as to cause the ball to roll toward the opposite end thereof and thereby complete said tilting, a fragile chemical-receptacle supported in the tank and adapted to be struck and broken, when 25 the runway is so tilted, and thereby charge the water with the chemical, and means, when the water is so charged, for automatically closing the valve and thereby causing the pressure of the generated gas to force the 30 water from the tank.

5. In a sprinkler system, the combination of a chemical-tank having a column of water therein and an air-filled space above the water, an inlet-pipe leading into the tank for 35 conducting the water into said tank, which water is normally maintained at a certain level by the excess pressure above the column of water, an outlet-pipe leading from the tank, a system of piping with which the outlet-pipe connects, heat-operated means for 40 causing the piping to open up and thereby permit the extinguishing agent to sprinkle and discharge from the piping, a branch pipe leading from the outlet-pipe and extending 45 through the side of the tank, a valve at the inner open end of the branch pipe, means for normally holding said valve at an open position, a tilttable runway in the tank and having a weighted ball therein adapted to roll from 50 one end of the runway to the other, when said runway is tilted, an arm extending from the runway and carrying a contact, a float-ball adapted, when the system of piping is opened up by the heat generated from a fire and air-pressure on the water is thereby relieved, to be 55 raised by the then inflowing water, and when so raised to act upon the contact-arm and tilt one end of the runway so as to cause the ball to roll toward the opposite end thereof 60 and thereby complete said tilting, a fragile chemical-receptacle supported in the tank and adapted to be struck and broken when the runway is so tilted, and thereby charge the water with the chemical, and means, 65 when the water is so charged, for automatically

ally closing the valve and thereby causing the pressure of the generated gas to force the chemically-impregnated water from the tank.

6. In a sprinkler system, the combination of a chemical-tank having a column of water 70 therein and an air-filled space above the water, an inlet-pipe leading into the tank for conducting the water into said tank, which water is normally maintained at a certain level by the excess pressure above the column of water, an outlet-pipe leading from the tank, a system of piping with which the outlet-pipe connects, heat-operated means for 75 causing the piping to open up and thereby permit the extinguishing agent to sprinkle and discharge from the piping, a branch pipe leading from the outlet-pipe and extending through the side of the tank, a valve at the inner open end of the branch pipe, means for normally holding said valve at an open position, a tilttable runway in the tank having a weighted ball therein adapted to roll from one end of the runway to the other, when 80 said runway is tilted, an arm extending from the runway and carrying an adjustable contact, a float-ball adapted, when the system of piping is opened up by the heat generated from a fire and air-pressure on the water is thereby relieved, to be raised by the then inflowing water, and when so raised to act upon 85 the contact-arm and tilt one end of the runway so as to cause the ball to roll toward the opposite end thereof and thereby complete said tilting, a fragile chemical-receptacle supported in the tank and adapted to be struck and broken when the runway is so tilted and thereby charge the water with the chemical, and means, when the water is so charged, for 90 automatically closing the valve and thereby causing the pressure of the generated gas to force the chemically-impregnated water from the tank.

7. In a sprinkler system, the combination of a chemical-tank having a column of water therein and an air-filled space above the water, an inlet-pipe leading into the tank for 100 conducting the water into said tank, which water is normally maintained at a certain level by the excess pressure above the column of water, an outlet-pipe leading from the lower portion of the tank, a system of piping with which the outlet-pipe connects, heat-operated means for 105 causing the piping to open up and thereby permit the extinguishing agent to sprinkle and discharge from the piping, a branch pipe leading from the outlet-pipe and extending through the side of the tank, a valve at the inner open end of the branch pipe, means for normally holding said valve at an open position, a tilttable runway in the tank having a weighted ball therein adapted to roll from one end of the runway to the opposite end thereof, when said runway is tilted, a chemical-receptacle carried by and tilttable with the runway, a float-ball 110

adapted, when the system of piping is opened up by the heat generated from a fire and air-pressure on the water thereby relieved, to be raised by the then inflowing water, and when so raised to act upon and tilt one end of the runway so as to cause the ball to roll toward the opposite end thereof and thereby complete said tilting and cause the dumping of the chemical contents of the receptacle into the water, and means, when the water is so charged with the chemical, for automatically closing the valve and thereby causing the pressure of the generated gas to force the chemically-charged water from the tank and through the system of piping and out of the discharge-openings of said piping.

8. In a sprinkler system, the combination of a chemical-tank having a column of water therein and an air-filled space above the water, an inlet-pipe leading into the tank for conducting the water into said tank, which water is normally maintained at a certain level by the excess pressure above the column of water, an outlet-pipe leading from the tank, a system of piping with which the outlet-pipe connects, heat-operated means for causing the piping to open up and thereby permit the extinguishing agent to sprinkle and discharge from the piping, a branch pipe leading from the outlet-pipe and extending through the side of the tank, a valve at the inner open end of the branch pipe, means for normally holding said valve at an open position, a tiltable runway in the tank having a weighted ball therein adapted to roll from one end of the runway to the opposite end thereof, when said runway is tilted, a chemical-receptacle carried by and tiltable with the runway, a float-ball adapted, when the system of piping is opened by the heat generated from a fire and air-pressure on the water thereby relieved, to be raised by the then inflowing water, and when so raised to act upon and tilt one end of the runway so as to cause the ball to roll toward the opposite end thereof and thereby complete said tilting and dump the chemical contents of the receptacle, a fragile receptacle for chemicals supported in the tank, and adapted to be struck and broken when the runway is so tilted, and thereby charge the water with the chemical contents thereof, and means, when the water is so charged with the chemicals, for automatically closing the valve and thereby cause the pressure of the generated gas to force the chemically-impregnated water from the tank and through the system of piping and out of the discharge-openings of said piping.

9. In a sprinkler system, the combination of a chemical-tank having a column of water therein and an air-filled space above the water, an inlet-pipe leading into the tank for conducting the water into said tank, which water is normally maintained at a certain level by the excess pressure above the column

of water, an outlet-pipe leading from the tank, a system of piping with which the outlet-pipe connects, heat-operated means for causing the piping to open up and thereby permit the extinguishing agent to sprinkle and discharge from the piping, a branch pipe leading from the outlet-pipe and extending through the side of the tank, a valve at the inner open end of said branch pipe, means for normally holding said valve at an open position, a tiltable chemical-agent-carrying frame, means, when a fire occurs and the system of piping is opened up by the generated heat, for automatically tilting the frame and dumping the chemicals into the water, and means, when the water is thus chemically charged for automatically closing the valve and thereby causing the pressure of the generated gas to force the water from the tank and through the outlet-pipe and into the system of piping and out of the discharge-openings of said piping.

10. In a sprinkler system, the combination of a chemical-tank having a column of water therein and an air-filled space above the water, an inlet-pipe leading into the tank for conducting the water into said tank which water is normally maintained at a certain level by the excess pressure thereabove, an outlet-pipe leading from the tank, a system of piping with which the outlet-pipe connects, heat-operated means for causing the piping to open up and thereby permit the extinguishing agent to sprinkle and discharge from the piping, a branch pipe leading from the outlet-pipe and extending through the side of the tank, a valve at the inner open end of said branch pipe, means for normally holding the valve at an open position, a tiltable chemical-agent-carrying frame, a float-ball adapted, when the system is opened up by the heat generated from a fire and air-pressure on the water thereby relieved, to be raised by the then inflowing water, and when so raised to act on the tiltable frame and dump the chemicals into the water, and means, when the water is so charged with chemicals, for automatically closing the valve and thereby causing the pressure on the generated gas to force the chemically-charged water from the tank and through the outlet-pipe into the system of piping, and out of the discharge-openings of said piping.

11. In a sprinkler system, the combination of a chemical-tank having a column of water therein and an air-filled space above the water, an inlet-pipe leading into the tank for conducting the water into said tank, which water is normally maintained at a certain level by the excess pressure thereabove, an outlet-pipe leading from the tank, a system of piping with which the outlet-pipe connects, heat-operated means for causing the piping to open up and thereby permit the extinguishing agent to sprinkle and discharge from the piping, a branch pipe leading from

the outlet and extending through the side of the tank, a valve pivoted at the inner open end of said branch pipe, a tiltable chemical-agent-carrying frame, said frame having a contact-arm normally engaging the valve and holding said valve at an open position, and means, when a fire occurs and the system of piping is opened up by the generated heat, for automatically tilting the frame and dumping the chemical into the water, the said tilting of the frame also withdrawing the contact-arm from engagement with the valve and permitting the closing of said valve, and thereby causing the pressure of the generated gas to force the chemically-charged water from the tank and through the outlet-pipe thereof and out of the discharge-openings of the system of piping.

12. In a sprinkler system, the combination of a chemical-tank having a column of water therein and an air-filled space above the water, an inlet-pipe leading into the tank for conducting the water into said tank, which water is normally maintained at a certain level by excess pressure thereabove, an outlet-pipe leading from the tank, a system of piping with which the outlet-pipe connects, heat-operated means for causing the piping to open up and thereby permit the extinguishing agent to sprinkle and discharge from the piping, a branch pipe leading from the outlet-pipe and extending through the side of the tank, a valve pivoted at the inner open end of said branch pipe, a tiltable chemical-agent-carrying frame, said frame having a contact-arm engaging the valve and normally holding said valve in an open position, and a float-ball adapted, when the system of piping is opened up by the heat generated from a fire and air-pressure on the water thereby relieved, to be raised by the then inflowing water, and when so arranged to act upon and tilt one end of the tiltable frame and thereby discharge the chemicals carried by the frame, and at the same time withdraw the contact-arm from engagement with the valve and allow said valve to automatically close, and thereby cause the pressure of the generated gas to force the chemically-charged water from the tank and through the outlet-pipe thereof, and through the system of piping and out of the discharge-openings of said piping.

13. In a sprinkler system, the combination of a chemical-tank having a column of water therein and an air-filled space above the water, an inlet-pipe leading into the tank for conducting the water into said tank, which water is normally maintained at a certain level by the excess pressure thereabove, an outlet-pipe leading from the tank, a system of piping with which the outlet-pipe connects, heat-operated means for causing the piping to open up and thereby permit the extinguishing agent to sprinkle and discharge

from the piping, a branch pipe leading from the outlet-pipe and extending through the side of the tank, a valve at the inner open end of said branch pipe, means for normally holding the valve at an open position, means, when a fire occurs, for chemically charging the water in the tank, means, when the water is so charged, for automatically closing the valve and thereby causing the pressure of the generated gas to force the chemically-charged water from the tank and through the outlet-pipe thereof and into the system of piping and out of the discharge-openings of said piping, an auxiliary tank, means for admitting a column of water therein, and for admitting a pressure agent above the column of water, and a pipe connecting the auxiliary tank with the chemical-tank.

14. In a sprinkler system, the combination of a chemical-tank having a column of water therein and an air-filled space above the water, an inlet-pipe leading into the tank for conducting the water into said tank, which water is normally maintained at a certain level by the excess pressure thereabove, an outlet-pipe leading from the tank, a system of piping with which the outlet-pipe connects, heat-operated means for causing the piping to open up and thereby permit the extinguishing agent to sprinkle and discharge from the piping, a branch pipe leading from the outlet-pipe and extending through the side of the tank, a valve at the inner open end of said branch pipe, means for normally holding the valve at an open position, means, when a fire occurs, for chemically charging the water in the tank, means, when the water is so charged, for automatically closing the valve and thereby causing the pressure of the generated gas to force the water from the tank and through the outlet-pipe thereof and into the system of piping and out of the discharge-openings of said piping, an auxiliary tank having a discharge-opening in its lower portion, means for admitting a column of water into the auxiliary tank, and for admitting a pressure agent above the column of water in said tank, a float-ball within the auxiliary tank and carrying a valve adapted to close the discharge-opening, when the water in the auxiliary tank lowers, and a pipe connecting the auxiliary tank with the chemical-tank.

15. In a sprinkler system, the combination of a chemical-tank having a column of water therein and an air-filled space above the water, an inlet-pipe leading into the tank for conducting the water into said tank, which water is normally maintained at a certain level by the excess pressure thereabove, an outlet-pipe leading from the tank, a system of piping with which the outlet-pipe connects, heat-operated means for causing the piping to open up and thereby permit the extinguishing agent to sprinkle and discharge

from the piping, a branch pipe leading from the outlet-pipe and extending through the side of the tank, a valve at the inner open end of said branch pipe, means for normally holding the valve at an open position, means, when a fire occurs, for chemically charging the water in the tank, means, when the water is so charged, for automatically closing the valve and thereby causing the pressure of the generated gas to force the chemically-charged water from the tank and through the outlet-pipe thereof and into the system of piping and out of the discharge-openings of said piping, an auxiliary tank, means for admitting a column of water in said tank and a pressure agent above the column of water, and a valve-controlled pipe connecting the auxiliary tank with the chemical-tank.

16. In a sprinkler system, the combination of a chemical-tank having a column of water therein and an air-filled space above the water, an inlet-pipe leading into the tank for conducting the water into said tank, which water is normally maintained at a certain level by the excess pressure thereabove, an outlet-pipe leading from the tank, a system of piping with which the outlet-pipe connects, heat-operated means for causing the piping to open up and thereby permit the extinguishing agent to sprinkle and discharge from the piping, a branch pipe leading from the outlet-pipe and extending through the side of the tank, a valve at the inner end of said branch pipe, means for normally holding the valve at an open position, means, when a fire occurs, for chemically charging the water in the tank, means, when the water is so charged, for automatically closing the valve and thereby causing the pressure of the generated gas to force the chemically-charged water from the tank and through the outlet-pipe thereof and into the system of piping and out of the discharge-openings of the piping, a water-pipe leading from a source of supply and with which the water-inlet pipe of the chemical-tank is connected, said pipe leading from the source of supply extending to and connecting with the system of piping.

17. In a sprinkler system, the combination of a chemical-tank having a column of water therein and an air-filled space above the water, an inlet-pipe leading into the tank for conducting the water into said tank, which water is normally maintained at a certain level by the excess pressure thereabove, an outlet-pipe leading from the tank, a system of piping with which the outlet-pipe connects, heat-operated means for causing the piping to open up and thereby permit the extinguishing agent to sprinkle and discharge from the piping, a branch pipe leading from the outlet-pipe and extending through the side of the tank, a valve at the inner end of said branch pipe, means for normally holding the valve at an open position, means, when a

fire occurs, for chemically charging the water in the tank, means, when the water is so charged, for automatically closing the valve and thereby causing the pressure of the generated gas to force the chemically-charged water from the tank and through the outlet-pipe thereof and into the system of piping and out of the discharge-openings of the piping, a water-pipe leading from a source of supply and with which the water-inlet pipe of the chemical-tank is connected, said pipe leading from the source of supply extending to and connecting with the system of piping, a valve in said pipe leading from the source of water-supply, and a valve in the water-pipe leading to the chemical-tank, said valves adapting the two systems to be used simultaneously, or independently of each other.

18. In a sprinkler system, the combination of a chemical-tank having a column of water therein and an air-filled space above the water, an inlet-pipe leading into the lower portion of the tank for conducting the water into said tank, which water is normally maintained at a certain level by the excess pressure above the column of water, an outlet-pipe leading from the tank, a system of piping with which the outlet-pipe connects, heat-operated means for causing the piping to open up and thereby permit the extinguishing agent to sprinkle and discharge from the piping, a branch pipe leading from the outlet-pipe and extending through the side of the tank, a valve at the inner open end of said branch pipe, means for normally holding the valve at an open position, a tilttable chemical agent-carrying frame, means, when a fire occurs, and the system of piping is opened up by the generated heat, for automatically tilting the frame and dumping the chemicals into the water, means, when the water is so charged, for automatically closing the valve and thereby causing the pressure of the generated gas to force the water from the tank and through the outlet-pipe and into the system of piping, and out of the discharge-openings of said piping, a main water-pipe leading from a source of supply, and with which main pipe the inlet-pipe of the chemical-tank is connected, said main pipe extending to and connecting with the system of piping.

19. In a sprinkler system, the combination of a chemical-tank having a column of water therein and an air-filled space above the water, an inlet-pipe leading into the tank for conducting the water into said tank, which water is normally maintained at a certain level by the excess pressure thereabove, an outlet-pipe leading from the tank, a system of piping with which the outlet-pipe connects, heat-operated means for causing the piping to open up and thereby permit the extinguishing agent to sprinkle and discharge from the piping, a branch pipe leading from the outlet-pipe and extending through the

- side of the tank, a valve at the inner open end of said branch pipe, means for normally holding the valve at an open position, a tiltable chemical-agent-carrying frame, a float-ball 5 adapted, when the system of piping is opened up by the heat generated from a fire, and the air-pressure on the water thereby relieved, to be raised by the then inflowing water, and when so raised to act on the tiltable frame 10 and dump the chemicals into the water, means, when the water is so charged with chemicals, for automatically closing the valve and thereby causing the pressure of the generated gas to force the chemically-charged 15 water from the tank and through the outlet-pipe and into the system of piping and out of the discharge-openings of said piping, a main water-pipe leading from a source of supply, and with which main pipe the inlet-pipe 20 of the chemical-tank is connected, said main pipe extending to and connecting with the system of piping.
20. In a sprinkler system, the combination of a chemical-tank having a column of water 25 therein and an air-filled space above the water, an inlet-pipe leading into the tank for conducting the water into said tank, which water is normally maintained at a certain level by the excess pressure thereabove, an outlet-pipe leading from the tank, a system 30 of piping with which the outlet-pipe connects, heat-operated means for causing the piping to open up and thereby permit the extinguishing agent to sprinkle and discharge from the piping, a branch pipe 35 leading from the outlet-pipe and extending through the side of the tank, a valve at the inner open end of said branch pipe, means for normally holding the valve at an open position, means, 40 when a fire occurs, for chemically charging the water in the tank, means, when the water is so charged, for automatically closing the valve and thereby causing the pressure of the generated gas to force the chemically-charged 45 water from the tank and through the outlet-pipe thereof and into the system of piping, and out of the discharge-openings of said piping, an auxiliary tank, means for admitting a column of water therein and a pres- 50 sure agent above the column of water, a pipe connecting the auxiliary tank with the chem-
- ical-tank, a main water-pipe leading from a source of supply, and with which main pipe the inlet-pipe of the chemical-tank is connected, said main pipe extending to and connected with the system of piping. 55
21. In a sprinkler system, the combination of a chemical-tank having a column of water therein and an air-filled space above the water, an inlet-pipe leading into the tank for 60 conducting the water into said tank, which water is normally maintained at a certain level by the excess pressure thereabove, a water-gage on the tank indicating the level of water therein, an outlet-pipe leading from 65 the tank, a system of piping with which the outlet-pipe connects, heat-operated means for causing the piping to open up and thereby permit the extinguishing agent to sprinkle and discharge from the piping, a branch pipe 70 leading from the outlet-pipe and extending through the side of the tank, a valve at the inner open end of said branch pipe, means for normally holding the valve in an open position, means, when a fire occurs, for chem- 75 ically charging the water in a tank, means, when the water is so charged, for automatically closing the valve and thereby causing the pressure of the generated gas to force the chemically-charged water from the tank and 80 through the outlet-pipe thereof and into the system of piping, and out of the discharge-openings of said piping, a pressure-indicator communicating with the tank, a safety-valve leading from the tank, an auxiliary tank, 85 means for admitting a column of water therein and a pressure agent above the column of water, a water-gage on the auxiliary tank, a pressure-gage on the auxiliary tank, a pipe connecting the auxiliary tank with the chem- 90 ical-tank, a main water-pipe leading from a source of supply, and with which main pipe the inlet-pipe of the chemical-tank is connected, said main pipe extending to and connected with the system of piping. 95

In testimony whereof I affix my signature in presence of two witnesses.

STEPHEN C. RADFORD.
